ALFRED HEALD, OF PHILADELPHIA, PENNSYLVANIA, ASSIGNOR TO
McCALLUM, CREASE & SLOAN, OF SAME PLACE.

Design No. 4,494, dated November 29, 1870.

DESIGN FOR A CARPET-PATTERN.

The Schedule referred to in these Letters Patent and making part of the same.

I, ALFRED HEALD, of Philadelphia, county of Philadelphia, State of Pennsylvania, have invented or produced a Design for a Carpet-Pattern, of which the following is a specification.

The figure in the accompanying drawing represents a sufficient of a carpet-pattern to illustrate my design, the remainder being merely a repetition of that which appears.

The pattern consists of a central medallion, A, in which is an ornament, *a*, and of tablets B B and C C, bounded by ornamented stripes D, the latter being arranged at right angles to each other.

The tablets B and C are of the character represented, one-fourth only of each of these tablets being shown in the drawing.

Irrespective of the colors employed,
I claim—

1. The design for the ornamented central medallion, as shown and described.

2. The design for the tablets B bounded by the ornamented stripes D.
3. The design for the ornamented tablets C bounded by the stripes D, as described and represented.
4. The design for the ornamented stripes D, arranged at right angles to each other, as shown and described.
5. The design for the entire pattern, including the medallion A, tablets B and C, and ornamented stripes D.

In testimony whereof, I have signed my name to this specification in the presence of two subscribing witnesses.

ALFRED HEALD.
